UNITED STATES PATENT OFFICE.

GOTTDANK L. KOTHNY AND ROBERT SUCZEK, OF PHILADELPHIA, PENNSYLVANIA,
ASSIGNORS TO C. H. WHEELER MANUFACTURING COMPANY, OF PHILADELPHIA,
PENNSYLVANIA, A CORPORATION OF PENNSYLVANIA.

FLUID-COMPRESSING APPARATUS.

1,282,595.

Specification of Letters Patent. Patented Oct. 22, 1918.

Application filed July 11, 1917. Serial No. 179,859.

To all whom it may concern:

Be it known that we, GOTTDANK L. KOTHNY and ROBERT SUCZEK, subjects of the Emperor of Austria-Hungary, residing at 5 Philadelphia, county of Philadelphia, State of Pennsylvania, have invented new and useful Improvements in Fluid-Compressing Apparatus, of which the following is a specification.

10 Our invention relates to apparatus for compressing fluid, such as air, gas, vapor, or a mixture of any of them, and involves the ejector principle in accordance with which a motive fluid, such as steam under 15 pressure, is allowed to expand and entrain the fluid to be compressed, the mixture of the fluids being delivered into a diffuser and discharged therefrom at a pressure higher than the initial pressure of the fluid to be 20 compressed.

Our invention resides in ejector apparatus wherein a jet of motive fluid issues in a sheet in the form of a disk, cone, or other suitable shape, from a nozzle comprising 25 members spaced from each other to form a nozzle passage communicating at its inner end with a throat formed within one of the nozzle members and having constant area within said nozzle member, the jet from the 30 nozzle entraining or carrying with it the fluid to be compressed into a diffuser surrounding or aligned with the nozzle and delivering into a discharge passage or casing, the nozzle and diffuser passages being 35 circumferentially continuous.

Our invention resides also in nozzle structure of the character referred to, in which the nozzle member other than that having the throat therein has a projection opposite 40 the throat to form a suitably curved nozzle passage beginning at the throat and curving into the principal part of the nozzle passage.

Our invention resides also in nozzle structure of the character described in which the nozzle forming members are adjustable toward and away from each other to change the dimension of the nozzle passage beyond the throat, preferably without varying the 50 area of the throat, though the area of the throat may also be varied when the aforementioned projection is of length sufficient to be adjusted into the throat, thereby decreasing the throat area.

Our invention resides also in apparatus 55 of the character described in which the diffuser has a throat intermediate its inlet and outlet and preferably of a width less than the width of the outlet of the co-operating nozzle.

Where the elastic fluid is to be compressed to very much higher pressure, multi-stage 60 ejector apparatus may be employed wherein in the well known manner an ejector in one stage partially raises the pressure of a fluid 65 to be operated upon and delivers into a separate and serially connected ejector which further raises the pressure of the fluid to be operated upon, each ejector comprising 70 nozzle structure for expanding motive fluid and diffuser structure receiving the motive fluid and fluid entrained thereby and increasing their pressure.

Our invention resides in such multi-stage 75 ejector apparatus comprising separate ejectors connected in series and in which in an earlier stage there is employed any suitable type of ejector apparatus, while in a later stage there is employed separate ejector apparatus which comprises an expansion nozzle 80 delivering a jet of motive fluid in the form of a circular sheet or disk, hollow cone, or other suitable shape, into a surrounding or aligned diffuser, whereby in such second stage a relatively short jet of large entraining surface is available for raising the fluid to be operated upon to higher pressure, the nozzle of such later stage ejector being adjustable as to the width of its passage, such 85 nozzle adjustment being particularly suitable where there is employed in the separate ejector of an earlier stage nozzle and diffuser structure all of whose passages are of invariable cross section; and our invention resides also in multi-stage apparatus of the 90 character referred to in which in a later stage the annular diffuser passage may be adjusted as to width.

Our invention resides also in multi-stage 95 apparatus of the character above referred to 100 in which the fluid delivered by an earlier stage is divided into streams flowing to opposite sides of the motive fluid jet of a later stage.

Our invention resides also in multi-stage 105 apparatus in which in an earlier stage the area of the outlet or outlets of the nozzle or nozzles is less than or equal to the

area of the associated diffuser passage at its throat, while in a later stage the area of the nozzle outlet is greater than or equal to the area of the associated diffuser passage at 5 its throat.

Our invention resides in the foregoing features and other features hereinafter described.

For an illustration of several examples of 10 apparatus embodying our invention reference is to be had to the accompanying drawings, in which:

Figure 1 is a cross sectional view of radial jet apparatus embodying features of our invention.

Fig. 2 is a side elevational view of one of the nozzle members of Fig. 1.

Fig. 3 is a side view of the coöperating nozzle member of Fig. 1.

Fig. 4 is a cross sectional view, on larger scale, through a diffuser and associated nozzle, the latter of a structure differing somewhat from the nozzle of Fig. 1.

Fig. 5 is a cross sectional view of a diffuser and associated nozzle of different type.

Fig. 6 is a cross sectional view through a modified construction.

Fig. 7 is a fragmentary sectional view of a structure similar to that of Fig. 6, differing, however, as to the type of nozzle.

Fig. 8 is a vertical sectional view through a double stage apparatus.

Fig. 9 is a side elevational view of the apparatus shown in Fig. 8.

Fig. 10 is a vertical sectional view of a modified form of double stage apparatus.

Fig. 11 is an elevational view of a further arrangement of double stage apparatus.

Referring to Fig. 1, live or exhaust steam, 40 or other motive fluid of suitable character and suitable pressure, as compressed air or gas, is delivered from a source thereof, not shown, through passage A to the annular expansion nozzle B comprising the disks or 45 other members C, C¹, shown in side view in Figs. 2 and 3. Within the member C¹ is formed the throat T, of constant area. And opposite the throat T on the member C is the projection t, suitably curved to form a 50 curved passage from the throat T to the radial nozzle passage B.

Surrounding the nozzle is the annular diffuser comprising the members H, H¹ between which is formed a passage which converges to the throat q and then diverges to the periphery where it communicates with the discharge casing or passage F.

At A¹ is the inlet for the fluid which is to be raised to higher pressure, as for example, 60 fluid from an earlier stage, ejector or air or uncondensable gases or vapors from a steam condenser within which there is maintained a high vacuum. From A¹ the entering stream of fluid is divided into two streams 65 delivered through the passages p, p, to the

chambers D, D, on opposite sides of the jet issuing from the nozzle B.

The apparatus may be constructed in the form illustrated in Fig. 1, in which casing members E, E¹ are secured together at the 70 joint r as by bolts e, e to form the chambers D, D and the discharge passage F which has the outlet F². Secured centrally upon the casing E is the member a supporting the nozzle member C having the shank b movable in a recess in the member a and having the extension c threaded at s in the member a and extending to the exterior thereof and terminating in a squared or other suitably shaped end d for receiving a wrench or the 75 like for rotating the screw threaded member c to cause lateral adjustment of the nozzle member C toward or away from its companion member C¹. A nut f serves to lock the member C in its adjusted position, and a 80 cap g carried by the member a incloses the end of the member c and the nut f.

Supported centrally on the casing member E¹ is the member a¹ within which is formed the passage A and which carries the 85 nozzle member C¹. The diffuser wall H¹ is carried by the casing member E¹ and is integral therewith, or may be separate therefrom and suitably attached thereto. The other diffuser wall H is supported upon the casing 90 member E and is adjustable laterally toward or away from its companion member H¹ by the adjusting bolts b¹.

The passages p, p are formed within the 95 casing members E, E¹ and terminate at the upper flange c¹ to which is secured at joint r a flange of the member d¹, within which are formed passages registering with the 100 passages p, p and combining into a single passage at A¹.

The steam delivered to the nozzle B issues 105 therefrom in a jet radiating outwardly in all directions, and entraining the fluid to be compressed, which enters at A¹ and passes through the passages p, p to the chambers 110 D, D from which it issues through the annular passages p¹, p¹ into contact with opposite sides of the jet, the mixture being delivered into the diffuser passage, where it 115 loses its velocity and increases in pressure and is delivered into the discharge casing and issues therefrom through the outlet F².

The fluid operated upon may be raised in 120 pressure from a pressure below, equal to or higher than atmospheric pressure to suitable higher pressure. And in the case where uncondensable gases or vapors are to be removed from a steam condenser they are raised from a very low pressure, as for example 125 29 inches or more of vacuum, as measured by the mercury column, to higher pressure. And in the case where the apparatus shown in Fig. 1 is in a later stage of multi-stage apparatus, it receives the fluid partially composed from an earlier stage 130

through the passage A¹ and raises it to any suitable higher pressure below, equal to or above atmospheric pressure.

With a nozzle of the character illustrated in Fig. 1, the throat T is formed within one of the nozzle members and is of constant area, thereby delivering substantially constant amount of motive fluid, at a given motive fluid pressure. Adjustment of the nozzle member C, however, will increase or decrease the width of the nozzle passage B and so vary the expansion within the nozzle passage while the motive fluid consumption remains substantially the same. This adjustment of the nozzle also effects a change in the entraining surface of the free jet between the periphery of the nozzle and the point of impact upon the diffuser walls. When the member C is moved toward the member C¹ the jet becomes thinner, and therefore longer before impact upon the converging walls of the diffuser, and so increases the lateral entraining surface of the jet into contact with which comes the fluid to be compressed.

However, when the projection t is long enough to enter the throat T, as shown, adjustment of the member C will cause such projection t to project into the throat T to varying distances, and due to the fact that the projection t increases in diameter toward its base, the throat area is varied, and therefore the steam consumption is varied, along with adjustment of width of the nozzle passage B.

For different adjustments of the member C different adjustments of the diffuser wall H may be made if desired, or with a given nozzle setting the wall H may be adjusted. It will be understood, however, that the diffuser wall H may be non-adjustable or fixed with respect to its companion H¹.

It is preferred that the width w of the nozzle passage at its periphery shall be greater than the width of the diffuser passage at its throat q. By such structure the free jet of motive fluid issuing from the nozzle may be made relatively short; since its width is greater than the width of the diffuser throat, it impinges upon the converging walls of the diffuser passage at a point more and more distant from the diffuser throat toward the center of the apparatus as the jet increases in width. This is of advantage in that a short jet maintains its form and does not break up to any considerable extent before impact upon the diffuser walls. Notwithstanding this shortness of jet the diameter of the nozzle, that is, the diameter of either the members C, C¹ is small enough to insure lateral entraining surfaces of the jet of magnitude sufficient for entraining the elastic fluid to be compressed and raising it to considerably higher pressure in the diffuser. This structure is par-

ticularly suitable for ratios of compression which are relatively high, for example, greater than 2.

It will be understood that our invention is not, however, limited to the employment of a width of nozzle outlet which is greater than the width of the diffuser at its throat, for where low compression ratios are involved the width of the nozzle outlet may be less than or equal to the width of the diffuser passage at its throat.

While the opposing faces of the nozzle members C and C¹ are shown parallel with each other, it will be understood that they may diverge from each other toward their peripheries or may even converge somewhat toward their peripheries. In any case, when using elastic motive fluid, the nozzle passage increases in cross sectional area toward its periphery in order that the motive fluid may expand within the nozzle.

And while the diffuser passage is shown as increasing in width beyond throat q toward its periphery, it will be understood that the opposing faces of the diffuser walls may be parallel from the throat q outwardly or may even converge slightly.

At the bottom of each of the chambers D is provided a cock c² for draining off water or liquid which may accumulate.

In Fig. 4 there is shown, on enlarged scale, the nozzle and diffuser structure shown in Figs. 8 and 10. In this case the throat T of the nozzle is formed wholly within the nozzle member C¹, and is of constant area. The projection t in this instance is not of a length to project far enough into the throat T upon adjustment of the nozzle member C to cause variation of the throat area. Here again the width w of the nozzle passage at its periphery is greater than the width of the diffuser passage at its throat q. And while the opposing faces of the nozzle members C, C¹ are illustrated as parallel, they may converge or diverge toward their peripheries, as described in connection with Fig. 1.

In Fig. 5 is shown an arrangement in which the nozzle member C has a cavity or depression x at its center opposite the outlet of the passage A in the opposing nozzle member C¹. This structure causes the throat T to be formed at the region indicated between the two nozzle members C and C¹, and not within one of the nozzle members, as in Figs. 1, 4, 6, 8 and 10. In this case the throat is not an aperture located within one of the nozzle members, as in Figs. 1 and 3, but is of annular or ring form continuous throughout an entire circumference whose diameter is that indicated in Fig. 5. In this case the adjustment of the member C toward and away from the member C¹ adjusts the area of the throat, because the width of the throat is varied, though its diameter remains the

same, the throat area in this case being found by multiplying the width of the throat by the circumference at the point or region of closest approach to the members C, C¹ to 5 each other. While the opposing faces of the nozzle members are in this case shown divergent toward the periphery, it will be understood that they may be parallel or slightly convergent. And in any event, when 10 elastic motive fluid is employed, the area of the nozzle opening at its periphery is greater than at its throat.

The nozzle structure of Figs. 1, 4, 6, 8 and 15 10, is such that the nozzle passage from throat to nozzle outlet causes the motive fluid to change its direction of flow, as from axial to normal to the axis or to any suitable angle with the axis, the motive fluid expanding while so changing its direction of flow. 20 In Fig. 6 the arrangement is such that the nozzle is cone-shaped, producing a jet in the form of a hollow cone. The coöperating diffuser H is also cone-shaped and aligned with the nozzle, which latter has the general 25 characteristics of the nozzle illustrated in Fig. 4.

In Fig. 7 a like conical arrangement of nozzle and diffuser is shown, but the nozzle is of the general character illustrated in 30 Fig. 5.

Because of the greater facility and cheapness in construction, the nozzles and diffusers of Figs. 1, 4, 5, 8 and 10 are preferred over the conical forms of Figs. 6 and 7.

35 It will further be understood concerning the diffusers of Figs. 4 to 8 inclusive and Fig. 10 that the width of the diffuser passage may be adjusted as by means illustrated in Fig. 1; or the width of the diffuser passages may be altered to any suitable dimension, as by placing in or removing from the joints r of either or both diffuser members a gasket or other separating piece.

And in all cases it is preferred that the 45 diffuser passage shall decrease in cross sectional area to its minimum area at the throat q and then increase in area outwardly to the periphery of the diffuser. Beyond the throat q the adjacent sides of the diffuser members 50 need not actually diverge as indicated, but may be parallel or even slightly convergent, in which case it is still possible that the cross sectional area of the diffuser passage at the periphery of the diffuser may be greater than at the throat q.

By the foregoing relations of nozzle and diffuser structure compression of one elastic fluid by another is highly efficient, particularly when the ratio of compression is 2 or 60 greater than 2; that is to say, when the pressure to which the fluid is compressed is twice or more than twice its pressure before compression.

Referring to Figs. 8 and 9, double stage 65 apparatus is shown wherein in the first stage

is employed a common form of ejector, which may be termed a tubular ejector, and in the second stage an ejector of the radial jet type. From Fig. 9 have been omitted the pipe g, valve h, the vertical portion of pipe 70 n, and the housing of strainer i, shown in Fig. 8.

Live or exhaust steam, or other suitable motive fluid, is delivered through a pipe g, controlled by valve h, and through a strainer 75 i, valve m and pipe n and strainer i' through the expansion nozzles N, of any suitable number, each having a throat of constant area and nozzle passage of fixed dimensions. The motive fluid issues in jets from the nozzles N into the space or chamber D¹ in communication through the opening A¹ with the space containing the elastic fluid to be compressed, as for example, the interior of a steam condenser or the like, in which high 80 vacuum is to be maintained. The motive fluid jets entrain elastic fluid to be compressed, and the mixture passes into the diffuser d, here shown tubular in shape, converging from the point d² to the throat o, 85 and diverging below the same to the point d³. The mixture of the two fluids is discharged at d³ at higher pressure than that of the elastic fluid entering at A¹, into the passages p, p connecting the separate first and second 90 stages ejectors in series and communicating with the chambers D, D on opposite sides of the jet issuing from the annular nozzle B in the second stage.

Steam or other motive fluid is simultaneously delivered through the strainer i into the passage A, which communicates with the annular expansion nozzle B formed between the circular or other suitably shaped plates or disks C, C¹ adjustable as to their separation by the screw s.

The jet from the nozzle B entrains elastic fluid from the chambers D, D and carries it into the annular diffuser H, from which the mixture is discharged into the casing F having the discharge outlet F¹.

In this second stage the pressure of the elastic fluid is again raised and in the discharge casing F the pressure is higher than in the chambers D, D, and the pressure in the casing F may be atmospheric pressure or higher, or any other desired pressure.

By closing the valve m the apparatus may operate as a single stage compressor, the elastic fluid being drawn in through the opening A¹, through diffuser d into the passages p, p into the chambers D, D, where it is compressed in one stage to desired pressure.

The lines r indicate joints or lines of division between the castings or metal parts of the apparatus, the parts being divided in manner to facilitate construction, finishing, assembly and adjustment.

The second stage apparatus comprises the 120

casing members E and E¹ forming the discharge passage F and the chambers D, D. One ring shaped diffuser member is secured by its ring shaped lateral flange or lug h¹ 5 to the member E and the other to the member E¹. The lower parts of the passages p, p are formed in tubular members integral with the casing members E and E¹. Upon the upper ends of these tubular members are secured 10 the lower ends of similar tubular members, which form a union near the top flange c¹ to which is secured the lower or discharge end d³ of the diffuser d of the first stage. By this construction the fluid delivered 15 from the diffuser d of the first stage passes indirectly and in divided streams to the upper parts of the chambers D, D and then flows throughout these chambers and the lower parts as well to both sides of the 20 jet from the nozzle B which issues upwardly, downwardly and laterally in all directions, that is, radially, to the diffuser H.

In Fig. 10 is shown a double stage apparatus in which in both stages the apparatus 25 is of the character illustrated in the second stage of Fig. 8. The elastic fluid to be compressed enters at A¹ and passes to the chambers D, D, from which it is entrained by the jet of motive fluid from the nozzle B, 30 and the mixture passes through the diffuser H into the discharge casing F, from which it is discharged indirectly and in divided streams through the passages p, p into the chambers D¹, D¹ of the second stage, to opposite sides of the jet from the nozzle B¹, 35 by which it is entrained, and the mixture is delivered into the diffuser H², having its throat at q¹, and is discharged into the discharge casing F¹ having the outlet F².

40 By this construction again the elastic fluid entering at A¹ is compressed in two successive stages, from any suitable pressure below, equal to or above atmospheric pressure, to any suitable higher pressure, and as 45 in the case of Figs. 8 and 9 is suitable for withdrawing air or uncondensable gases or vapors from a steam condenser for maintaining therein a high vacuum, as for example 29 inches more or less, as measured 50 on the mercury column, and for compressing such gases or vapors to any other suitable higher pressure, as for example atmospheric pressure or higher.

In Fig. 11 there is shown in elevation a 55 double stage apparatus in which the units are placed side by side and the discharge from one unit is delivered through the pipe P to the intake of the second stage unit, motive fluid, as steam, being supplied by the 60 pipe g and delivered through the valve m through the first stage ejector apparatus and through the valve h to the second stage apparatus.

In the double stage arrangements the best 65 operation is obtained when in the first stage

the total nozzle outlet area is less than the area of the diffuser passage at its throat, though these areas may be equal; while in the second stage the area of nozzle outlet is greater than the area of the diffuser 70 passage at its throat, though these areas may be equal. As regards the apparatus producing a radial jet, the area of the nozzle opening is found by multiplying the width w by the circumference of the nozzle outlet; and the area at the diffuser throat is found by multiplying the width of the throat by the circumference of a circle whose radius is equal to the distance of the 75 throat from the center of the nozzle. 80

And where the radial jet type of apparatus is used in both stages, it is desirable that the width of the nozzle opening at w shall be greater than the width of the throat of the diffuser in both stages, unless in any stage the ratio of compression is low, in which case the width of the nozzle opening w in that stage may be equal to or less than the width of the diffuser passage at its 85 throat. 90

For the sake of brevity in the appended claims the terms "annular nozzle" and "annular diffuser" will be understood to include nozzles and diffusers having passages which are either at right angles to the longitudinal axis and producing and receiving respectively a disk shaped jet, as in Figs. 1, 4, 5, 8 and 10, or whether conical, as in Figs. 6 and 7, wherein the jet is thin and of cone shape. 95

This application is in part a continuation of our applications serially numbered 85,045 and 135,371, filed respectively March 18 and December 6, 1916.

What we claim is:

1. Ejector apparatus comprising a diffuser and a coöperating annular motive fluid nozzle comprising nozzle members spaced from each other to form a nozzle passage, the throat of said nozzle passage 110 formed within one of said members.

2. Ejector apparatus comprising a diffuser and a coöperating annular motive fluid nozzle comprising nozzle members spaced from each other to form a nozzle 115 passage, the throat of said nozzle passage formed within one of said members, and a projection on the other of the nozzle members projecting toward said throat.

3. Ejector apparatus comprising a diffuser and a coöperating annular motive fluid nozzle comprising nozzle members spaced from each other, the throat of said nozzle formed within one of said members and communicating with the outlet of the 120 nozzle through a curved passage. 125

4. Ejector apparatus comprising a diffuser and a coöperating annular motive fluid nozzle comprising nozzle members spaced from each other to form a nozzle 130

- passage, the throat of said nozzle passage located within one of said members, said nozzle passage changing the direction of flow of the motive fluid while expanding 5 from the throat outwardly.
5. Ejector apparatus comprising a diffuser and a coöperating annular motive fluid nozzle comprising nozzle members spaced from each other to form a nozzle passage, a 10 throat of said nozzle passage formed within one of said members, and a curved wall extending from said throat to the face of said one of said members.
6. Ejector apparatus comprising a diffuser and a coöperating annular motive fluid nozzle comprising nozzle members spaced from each other to form a nozzle passage, the throat of said nozzle passage formed within one of said members at a 15 distance from the face of said one of said members.
7. Ejector apparatus comprising a diffuser and a coöperating annular motive fluid nozzle comprising nozzle members spaced from each other to form a nozzle passage, a 20 throat formed within one of said members, a curved wall extending from said throat to the face of said one of said members, and a projection on the other of said nozzle 25 members having a curved wall forming with said first named curved wall a curved 30 passage from the throat to the space between said nozzle members.
8. Ejector apparatus comprising a diffuser and a coöperating annular motive fluid nozzle comprising nozzle members spaced from each other to form a nozzle passage, a 35 throat formed within one of said members, and means for adjusting said nozzle members with respect to each other to change 40 the width of the nozzle passage without substantially varying the area of said throat.
9. Ejector apparatus comprising a diffuser and a coöperating annular motive fluid nozzle comprising nozzle members spaced from each other to form a nozzle passage, a 45 throat formed within one of said members, a projection on the other of the nozzle members projecting toward said throat, and 50 means for adjusting said nozzle members with respect to each other.
10. Ejector apparatus comprising an annular nozzle comprising stationary members spaced from each other to form a nozzle 55 passage, said nozzle passage having a throat located within one of said members and substantially at its center.
11. In ejector apparatus, an annular nozzle comprising nozzle members spaced from each other to form a nozzle passage, the nozzle throat formed within one of said members, an annular diffuser surrounding 60 said nozzle, said diffuser having a throat intermediate its inlet and outlet, and means
- for adjusting said nozzle members with respect to each other. 65
12. In ejector apparatus, the combination with an annular nozzle comprising nozzle members spaced from each other to form a nozzle passage, the nozzle throat formed within one of said nozzle members and having constant area, an annular diffuser surrounding said nozzle and having a throat intermediate its inlet and outlet, and means for adjusting said nozzle members with respect to each other. 70
13. Ejector apparatus comprising an annular nozzle, a coöperating diffuser, said nozzle comprising members spaced from each other to form a nozzle passage, said 75 nozzle passage having a throat within one of said members, means for adjusting the width of said nozzle passage, and means for adjusting the width of the diffuser passage. 80
14. In ejector apparatus, the combination with an annular nozzle, of an annular diffuser surrounding the same and having a throat intermediate its inlet and outlet, the width of the nozzle outlet being greater than the width of said diffuser throat. 85
15. In ejector apparatus, the combination with an annular nozzle, of an annular diffuser surrounding the same, said diffuser having a throat intermediate its inlet and outlet, the area of the nozzle outlet being greater than the area of the diffuser passage at said throat. 90
16. In ejector apparatus the combination with an annular nozzle, of an annular diffuser surrounding the same, said diffuser having a throat intermediate its inlet and outlet, the area of the nozzle outlet being greater than the area of the diffuser passage at said throat and the width of said nozzle outlet being greater than the width 100 of the throat of said diffuser. 105
17. Multi-stage ejector apparatus comprising in one stage an ejector, and in a later stage an ejector comprising an annular nozzle and an annular diffuser, and fluid connections from said one stage to opposite sides of the nozzle opening of the later stage. 110
18. Multi-stage apparatus comprising in one stage an ejector, and in a later stage 115 an ejector comprising an annular nozzle and an annular diffuser, and means for conducting fluid from said one stage in divided streams to opposite sides of the opening of said annular nozzle of the later stage. 120
19. In multi-stage apparatus, the combination with an ejector in one stage, of an ejector in a later stage comprising an annular nozzle, an annular diffuser, chambers on opposite sides of the nozzle outlet 125 and diffuser inlet, and fluid connections from the ejector of said one stage to said chambers.

20. In multi-stage apparatus, the combination with an ejector in one stage, of an ejector in a later stage comprising an annular nozzle, an annular diffuser, chambers on opposite sides of the nozzle outlet and diffuser inlet, and tubular connections with the ejector of said one stage delivering fluid therefrom in divided streams to said chambers at points thereof eccentric with respect to said annular nozzle. 65
21. In multi-stage apparatus, an ejector in one stage comprising nozzle and diffuser structure all of whose passages are of invariable cross section, an ejector in a later stage connected in series with said first ejector and comprising an annular nozzle, an annular diffuser, said diffuser having a throat intermediate its inlet and outlet, and means for adjusting the width of the passage of said annular nozzle with respect to the width of the throat of said diffuser. 75
22. In multi-stage apparatus, the combination with an ejector in one stage, of an ejector in a later stage comprising an annular nozzle and an annular diffuser, said nozzle formed of members spaced from each other to form the nozzle passage, the nozzle throat formed within one of said members, and means for adjusting said members for varying the width of the nozzle passage without substantial effect upon the area of said nozzle throat. 80
23. In multi-stage ejector apparatus, a tubular ejector in one stage comprising a plurality of motive fluid expanding nozzles and a coöperating diffuser common to them, said diffuser having a throat beyond which the diffuser passage diverges, a separate ejector in a later stage comprising an annular motive fluid expanding nozzle and a coöperating annular diffuser, means for adjusting the width of the passage of said annular nozzle with respect to the width of the throat of said annular diffuser, and means for connecting said ejectors in series communicating with the discharge end of said divergent diffuser passage of said tubular ejector and extending to opposite sides of the jet issuing from said annular nozzle in the later stage. 85
24. Multi-stage ejector apparatus comprising a plurality of serially connected ejectors each comprising nozzle structure co-operating with diffuser structure, said diffuser structure having a throat, the area of the outlet of the nozzle structure being less than the area of the diffuser passage at its throat in one stage, and the area of the outlet of the nozzle structure being greater than the area of the diffuser passage at its throat in a later stage. 90
25. Multi-stage ejector apparatus comprising in each of a plurality of stages an annular nozzle and an annular diffuser, said diffuser having a throat, the width of the nozzle outlet being greater than the width of the diffuser throat, the area of the nozzle outlet being less than the area of the diffuser passage at its throat in one stage, and the area of the nozzle outlet being greater than the area of the diffuser passage at its throat in a later stage. 95
26. Multi-stage ejector apparatus comprising independently operating serially connected ejectors, an ejector of a later stage comprising an annular nozzle and coöperating diffuser, and fluid connections connecting an ejector of an earlier stage to opposite sides of the outlet of said annular nozzle. 100
27. Multi-stage ejector apparatus comprising in one stage an ejector, and in a later stage an ejector comprising an annular nozzle and a coöperating diffuser, tubular members holding one of the ejectors in fixed relation with respect to another and serving to deliver fluid from an earlier stage ejector in divided streams to opposite sides of said annular nozzle. 105
28. Multi-stage ejector apparatus comprising in one stage an ejector, and in another stage an ejector comprising an annular nozzle, a coöperating diffuser and a discharge casing surrounding said diffuser, and tubular members communicating with opposite sides of said annular nozzle embracing said discharge casing and communicating with said first named ejector. 110
29. Two stage ejector apparatus for continuously removing elastic fluid from a chamber within which is maintained an absolute pressure less than three inches of mercury and for compressing the same to substantially atmospheric pressure comprising a tubular ejector in the first stage, a second ejector in the second stage comprising an annular motive fluid expanding nozzle and a coöperating diffuser, and means for connecting said ejectors in series communicating with the discharge end of said tubular ejector and extending to said second stage ejector and delivering on opposite sides of the motive fluid jet from said annular nozzle. 115
30. Multi-stage ejector apparatus comprising a tubular ejector having nozzle and diffuser structure, said diffuser structure having a throat beyond which the diffuser passage diverges, a second ejector comprising an annular motive fluid expanding nozzle and a coöperating diffuser, and means for connecting said ejectors in series communicating with the discharge end of the divergent passage of said diffuser structure of said first ejector and extending to said second ejector and delivering to opposite sides of the motive fluid jet from said annular nozzle. 120
- 125

31. Ejector structure comprising annular nozzle structure for expanding elastic motive fluid comprising stationary plate or disk members spaced from each other to form a nozzle passage, said nozzle passage having a restricted throat within one of said members, a projection on another of said members extending toward said throat, and means for adjusting said other of said mem-

bers with respect to said one of said members for adjusting the area of said throat and the width of said nozzle passage.

In testimony whereof we have hereunto affixed our signatures this 3rd day of July, 1917.

GOTTDANK L. KOTHNY.
ROBERT SUCZEK.

It is hereby certified that in Letters Patent No. 1,282,595, granted October 22, 1918, upon the application of Gottdank L. Kothny and Robert Suczek, of Philadelphia, Pennsylvania, for an improvement in "Fluid-Compressing Apparatus," errors appear in the printed specification requiring correction as follows: Page 2, line 94, for the word "attahed" read *attached*; same page, line 130, for the word "composed" read *compressed*; page 5, line 61, for the word "through" read *to*; and that the said Letters Patent should be read with these corrections therein that the same may conform to the record of the case in the Patent Office.

Signed and sealed this 19th day of November, A. D., 1918.

[SEAL.]

R. F. WHITEHEAD,
Acting Commissioner of Patents.

Cl. 230—13.
